UNITED STATES PATENT OFFICE.

WILLIAM B. KINGMAN, OF BROOKLINE, MASSACHUSETTS, ASSIGNOR TO HURLEY SHOE STORES COMPANY, OF ROCKLAND, MASSACHUSETTS, A CORPORATION OF MASSACHUSETTS.

SHOE.

Application filed October 14, 1922. Serial No. 594,598.

This invention relates to shoes which are provided with means for supporting the arch of the foot and has especial reference to shoes wherein the arch supporting means is incorporated in the shoe, as a component part thereof, as distinguished from arch-supporting means which are adapted to be inserted in the shoe and which necessarily decrease the size of the shoe, and render necessary a shoe larger than is otherwise needed.

An object of this invention is the provision of a shoe having one or a plurality of pockets built in the shoe and disposed at the shank portion thereof, and so arranged that a wearer of the shoe may insert a variable number of lifts of suitable thickness in said pockets, whereby to provide an arch support especially to meet this particular need.

Fig. 1 is a plan view of a shoe with the upper partially cut away to illustrate the invention.

Fig. 2 is a transverse section along line 2—2 of Fig. 1.

Fig. 3 is a perspective view of the secondary inner sole removed from the shoe and partially in section to illustrate more clearly the construction of the pockets thereof.

Fig. 4 is a plan view of the secondary inner sole.

Figs. 5 and 6 are plan views of different sizes of lifts adapted to be inserted in the pockets of the secondary inner sole.

Fig. 7 is a transverse sectional view through a lift.

The secondary inner sole 10 forming a part of the invention preferably is of leather and flexible. Said inner sole is adapted to be lasted in the shoe over the usual or primary inner sole 11 and is shaped to conform to the outline of said inner sole 11. Said secondary inner sole 10 is adapted to extend forwardly from the heel to about the ball portion of the foot and is or may be skived to a thin forward edge 12. Said secondary inner sole, preferably, is formed with a lateral extension 13 at its outer edge which is adapted to be formed over the outer edge of the primary inner sole 11 and be sewed to said inner sole 11 between said inner sole and the upper 14 by a line of stitches 15. Said secondary inner sole

10 is also provided with a short lateral extension or tab 16 on its forward and inner edge which is adapted to be formed over the inner edge of the primary inner sole and sewed to

and between said inner sole and upper. With 55 this arrangement, said secondary inner sole is permanently attached to the shoe while the heel-portion and major portion of the inner edge thereof are free from attachment to the shoe and may be flexed and raised to permit 60 the insertion of lifts in pockets of said secondary inner sole.

Said secondary inner sole 10 is formed with a plurality of pockets at its inner edge which are adapted to be disposed beneath the arch 65 of the foot. Said pockets may be provided by attaching to the under side of said inner sole 10 a plurality of superimposed flexible layers of, preferably, leather 18. Said superimposed layers extend from the inner edge of 70 and under said secondary inner sole and are or may be of more or less arcuate shape. The inner edges of said layers are united together and to said secondary inner sole by a line of stitching 20 and the overlapping inner edges 75 of said layers are preferably skived off to thin edges whereby to avoid an abrupt increase of thickness at said edges.

It is to be noted that the intermediate portion of said line of stitching 20 is inset substantially from the line of the inner edge of the primary inner sole 11 and, preferably, is located at the outer edge portion thereof whereby to permit the arch-supporting lifts to extend a substantial distance under the arch of 80 the foot whereby the better to support the arch.

The arch-supporting lifts 25 are or may be of various sizes and thicknesses and are or may be shaped to conform to the shape of the 90 pockets in the secondary inner sole; and are or may be skived to provide thin edges. The lift adapted to enter the lowermost pocket is or may be the largest and superimposed lifts may be smaller, whereby to provide a support, 95 the highest portion of which is under the highest part of the arch and which slopes gradually away to the inner sole.

By reason of the fact that the secondary inner sole is flexible and is free from attachment 100 with the shoe at the heel and inner edge or pocket portion thereof, whereby said portion may be raised, the lifts may be easily inserted and removed.

The secondary inner sole may be provided with any suitable number of superimposed pockets. The wearer of the shoe may insert lifts in as many pockets as may be necessary

to obtain suitable support. In some instances, but one lift may be needed; and in other instances, two or more lifts may be used.

I claim:

- 5 1. An arch-supporting shoe comprising, in combination with the usual upper and inner sole, a secondary inner sole overlying the inner sole and lasted in with the inner sole and the upper, said secondary inner sole having a free edge at the shank of the shoe and having a plurality of flexible sheets disposed in superposed order beneath said secondary sole, and means securing said sheets and said secondary inner sole together to form a plurality of superimposed pad-receiving pockets which are open at one side of the finished shoe, with the sheets and the secondary inner sole at the pocket-openings overlying the upper and the pocket-openings being readily accessible from the interior of the shoe, the sheets and secondary inner sole being flexible at the pockets to permit the pockets to be opened to permit the wearer to insert therein removable arch-supporting pads.
- 10 2. A shoe having an upper, a sole, and an arch-support all lasted together, said arch-support having a plurality of superposed open pockets which have therein differently-sized arch-supporting lifts, the side walls of said pockets overlying the upper and the openings to said pockets being open to the interior of the shoe beside the upper.
- 15 3. A shoe having an upper, a primary inner sole and a flexible secondary inner sole lasted in the shoe over said primary inner sole and having its heel portion and at least a substantial extent of its inner edge-portion free from attachment with the shoe, said secondary inner sole having therebeneath a plurality of superimposed flexible layers which together with said secondary inner sole overlie the upper, and a line of stitching passed through the edges of said layers and also through said secondary inner sole, whereby to unite all and form a plurality of superimposed pockets which are open at the free edge of said secondary inner sole and are readily accessible from the interior of the shoe and overlie the upper and are adapted to receive removable arch-supporting lifts, said secondary inner sole having its edge opposed to said pockets attached to the shoe.
- 20 4. A shoe having an upper, a primary inner sole and a flexible secondary inner sole lasted in the shoe over said primary inner sole and having its heel portion and at least

a substantial extent of its flexible inner edge-portion free from attachment with the shoe and overlying the upper thereat, said secondary inner sole having a pocket which is 60 open at said free edge and is adapted to receive a removable arch-supporting lift, said secondary inner sole having its edge opposed to said pocket attached to the shoe.

5. A secondary inner sole for shoes having a heel-portion, a shank portion formed with a pocket therein which has an opening at the inner edge of said inner sole and is adapted to receive a removable arch-supporting lift, an extension forward of said pocket, 65 and an extension on the outer edge of said inner sole, said extensions arranged to be attached to the shoe whereby to leave the heel-portion and major portion of the inner edge of the inner sole free from attachment with 70 the shoe.

6. A shoe having an upper and a primary inner sole, and a secondary inner sole received over said primary inner sole, said secondary inner sole having a pocket in the 80 shank-portion thereof adapted to receive a removable arch-supporting lift, a lateral extension at its inner edge forward of said pocket secured to the shoe between the primary inner sole and the upper, and a lateral 85 extension at its outer edge extended forward from the heel-portion and also secured to the shoe between the primary inner sole and the upper, said heel-portion and major portion of the inner edge of said secondary inner sole 90 being free from attachment to the shoe.

7. A shoe having an upper and a primary inner sole, and a flexible secondary inner sole received over said primary inner sole, said secondary inner sole having a plurality of superimposed layers thereof and a line of stitching passed through the inner edges of said layers, whereby to unite said layers and form a plurality of superimposed pockets adapted to receive removable arch-supporting lifts, said secondary inner sole also having a lateral extension at its inner edge forward of said superimposed pockets and secured to the shoe, and a lateral extension at its outer edge opposite said pockets and 100 also secured to the shoe, said heel-portion and major portion of the inner edge of said secondary inner sole being free from attachment 105 to the shoe.

In testimony whereof, I have signed my 110 name to this specification.

WILLIAM B. KINGMAN.
